UNITED STATES PATENT OFFICE

141,333

DESIGN FOR A WOVEN TEXTILE FABRIC

John Walther, New York, N. Y.

Application January 5, 1945, Serial No. 117,258

Term of patent 7 years

(Cl. D92—1)

To all whom it may concern:

Be it known that I, John Walther, a citizen of the United States of America, residing in New York city, county of New York and State of New York, have invented a new, original, and ornamental Design for a Woven Textile Fabric, of which the following is a specification, reference being had to the accompanying drawing, forming part thereof.

The figure is a plan view of a woven textile fabric showing my new design.

My design is characterized by the combina-

tion on a herringbone background, of alternating light and dark stripes, the darker stripe being wider, having a feather stitch-like appearance the direction of which is reversed to the direction of the herringbone background stripe at the apex of which each featherstitch-like stripe is placed as shown.

I claim:

The ornamental design for a woven textile fabric, substantially as shown and described.

JOHN WALThER.
